UNITED STATES PATENT OFFICE.

LEWIS S. WATRES, OF SCRANTON, PENNSYLVANIA, ASSIGNOR TO NATIONAL GRAPHITE LUBRICATION COMPANY, OF WILMINGTON, DELAWARE, A CORPORATION OF DELAWARE.

APPARATUS FOR ABRADING GRAPHITE OR SIMILAR MATERIAL.

Application filed July 11, 1924. Serial No. 725,377.

My invention relates to apparatus for effectively abrading solid material such, for example, as graphite, and introducing the same in regulated amounts into regions where it may perform a desired function.

In my prior Patent, No. 1,189,643, of July 4, 1916, I have described and claimed one form of apparatus for abrading graphite in the form of sticks, such apparatus being shown in conjunction with a locomotive boiler and arranged so as to introduce the graphite in finely divided form into the conduit supplying saturated steam to the superheater. My invention is an improvement over that described in said patent and while particularly adapted for use in connection with the saturated steam conduit of a locomotive, may be used for other purposes, and particularly for the lubrication of various moving parts either in a railway motor or other oscillating support.

The accompanying drawings illustrate a number of forms of my improved device. Fig. 1 is a perspective view with parts broken away of a locomotive boiler with a device of my invention installed; Fig. 2 is an enlarged view of an embodiment at present preferred by me, the cover-plate having been removed; Fig. 3 is a view mainly in vertical section of the construction shown in Fig. 2; Figs. 4 and 5 are similar views of a modification; Fig. 6 is an elevational view of a still further modification; and Fig. 7 is a view along line 7—7 of Fig. 6.

Referring to said drawings, 10 denotes a chamber casing having a stem 11 provided with a bore 11^a therethrough, and having a valve 12, to which is threaded a pipe 13 which may extend, when the device is mounted for use, through a locomotive boiler shell 14, and into the saturated steam conduit 15 shortly before the latter enters the manifold or header 16 for the superheater tubes 17.

A threaded stud 18 is preferably provided, by means of which casing 10 may be braced to the boiler shell 14. Mounted in casing 10 is an oscillating member of the pendulum type, the bob thereof being constituted by a generally horizontal portion 19, preferably of arcuate shape. Depending arms 20 and 21 are attached to both sides of said portion 19, and to the opposite ends of arms 20 and 21 are attached trunnions 22 and 23. Trunnion 22 is provided with a bearing 22^a, while

trunnion 23 has a bearing 23^a aligned with bearing 22^a and secured to casing 10. Arms 20 and 21 being made preferably of springy material allows trunnions 22 and 23 to be sprung into place. Casing 10 has a cover 24 which is clamped in place by means of bolts through holes in ears 25 provided around the casing 10. Member 19 carries in its middle portion an abrasive surface 26 which is preferably formed by embedding therein crystals of silicon carbide.

For the purpose of feeding solid material, such as graphite sticks onto the abrasive surface 26, I have provided a magazine 27 which is held in place by means of a collar portion 28 resting upon a shoulder 29 in the body of the chamber casing. A cap 30 engages in threaded relationship an annular extension 31 of casing 10, and is provided with an internal flange 32 which bears down upon the top of the collar portion 28 and holds it firmly against shoulder 29 whereby the tube 27 is held rigidly in place. I preferably provide a hole 27^a in tube 27 to insure equalization of pressure within the magazine. As the material to be abraded I prefer to use sticks 33 of compacted, flocculated graphite as made in accordance with the patent to George Kirkegaard, No. 1,185,682, of June 6, 1916.

In use my improved device may be mounted on a locomotive boiler, as shown in Fig. 1, being placed with the oscillator at right-angles to the longitudinal axis of the boiler. Before starting a run a number of the graphite sticks are placed in the magazine 27, valve 12 being of course shut off. Due to the lateral vibration or "noizing" of the locomotive, the oscillator will be kept in constant motion and will continue to abrade particles of the graphite sticks by the action of abrasive surface 26. Valve 12 being open, the particles produced by the abrasion of the graphite will find their way through bore 11^a into the stream of saturated steam on its way to the superheater, the presence of the graphite particles serving the dual purpose of effectively stopping up the incipient leaks in the couplings or joints of the superheater and lubricating the valves and pistons of the locomotive, all as more fully described in my aforementioned Patent, No. 1,189,643.

It will be noted that while there is no direct circulation of steam through the casing 10,

that there is a continual surging of the steam due to the action of cylinders. In addition a more or less diminished pressure results in casing 10 whenever the steam is cut off by means of throttle 34, while when the throttle is open full boiler pressure is immediately built up in said casing. Due to both these causes, the particles of the graphite are effectively carried out of casing 10.

10 In Figs. 4 to 6, inclusive, I have shown other forms of oscillating means. In Fig. 4 the oscillator consists of a comparatively heavy plate 40, the upper surface of which bears the abrasive material 41, the underside 15 being smooth and engaging rollers 42, having as bearings studs 43, 43 projecting from the casing 10'. The ends of the plate 40 may be provided with springs 44 which strike against opposite sides of the casing 10' and cause 20 plate 40 to rebound therefrom. Due to the sidewise vibration of the locomotive, plate 41 will oscillate back and forth and will abrade the graphite stick fed thereonto. In Fig. 6 a ball 50 travels on a support 51, and strikes 25 against the depending legs or stops 52, 52 of plate 53 having an abrading surface 54, and thus serves to move said plate back and forth.

The amount of graphite consumed will depend somewhat upon the weight of the material above the surface undergoing abrasion, 30 and the rate of consumption can therefore be to some extent controlled. If desired, a spring pressed follower may be employed in the magazine chamber.

35 It will be seen from the foregoing that I have provided a simple though exceedingly effective device for abrading and feeding graphite into the saturated steam conduit of a locomotive or in any region thereof in 40 which it might be desirable to admit such granular material. Furthermore, my device requires no external power means for its operation. It will also be apparent that various changes may be made in the detailed construction of my device, for which reason I do not 45 intend to limit my invention to such constructional details. For example, the oscillator member may be used to operate a separate abrading means in various ways which 50 will occur to the skilled mechanic.

I claim:

1. In combination a vibrating support, a chamber mounted thereon, a magazine tube extending into said chamber, an outlet from 55 said chamber, an oscillator within said chamber operated by the vibration of said chamber, and abrasive material within said chamber carried by said oscillator.

2. In combination a vehicle, a chamber 60 mounted thereon, a magazine tube extending

into said chamber, an outlet from said magazine tube, an oscillator within said chamber oscillated by vibration of said chamber, and abrasive material within said chamber carried by said oscillator.

3. An abrading apparatus adapted to be mounted upon a railway motor and comprising in combination a chamber, a magazine tube extending into said chamber, an outlet from 65 said magazine tube, an oscillator within said chamber operated by vibration of said chamber, an abrasive surface carried by said oscillator, said outlet being positioned so as to permit the feeding of material to be abraded onto said abrasive surface.

4. An abrading apparatus adapted to be mounted upon a railway motor and comprising in combination a chamber, a pendulum within said chamber, an abrasive surface carried by said pendulum, a magazine tube extending into 70 said chamber and positioned so as to permit the feeding of material to be abraded onto said surface.

5. An abrading apparatus adapted to be mounted upon a railway motor and comprising in combination a chamber, a pendulum within said chamber and having an approximately horizontal portion, an abrasive surface of arcuate shape carried by said horizontal portion, a magazine tube extending into 75 said chamber and positioned so as to permit the feeding of material to be abraded onto said surface.

6. An abrading apparatus adapted to be mounted upon a railway motor and comprising in combination a chamber, a pendulum within said chamber, said pendulum comprising two trunnioned depending members carrying an element extending in a substantially horizontal direction when said pendulum is 80 in its lowermost position, the upper surface of said horizontally extending element being abrasive, and a magazine tube extending into said chamber and between said depending members.

7. In combination, a vehicle, a chamber mounted thereon, an oscillator operated by transverse motion of said vehicle, and abrasive material in said chamber so associated with said oscillator that motion of said oscillator is transmitted to said abrasive material.

8. In combination, a vehicle, a chamber mounted thereon, an oscillator in said chamber adapted to be moved relative to the vehicle at an angle to the normal forward motion of said vehicle by the vibrating motion of said vehicle and abrasive material carried by said oscillator.

LEWIS S. WATRES.
